REFRIGERATOR

Louis Ruthenburg, Evansville, Ind., assignor to
 Servel, Inc., New York, N. Y., a corporation of
 Delaware

Application February 15, 1939, Serial No. 256,422

5 Claims. (Cl. 62—1)

My invention relates to refrigeration, and it is an object of the invention to provide an improved refrigerator having a set of drawers for receiving food or the like, wherein a space will be provided between the drawers and the door of the refrigerator so as to provide an auxiliary space for accommodating food articles that are most frequently used.

Another object of the invention is to provide a refrigerator of this character wherein means are provided on the front ends of the drawers for accommodating articles of food stored in the auxiliary space.

Another object of the invention is to provide an improved refrigerator having a main storage space and an auxiliary storage space in front thereof and separated therefrom and which is first accessible when the door of the refrigerator is open, wherein improved receptacles are provided for accommodating articles of food most frequently used and which are of such character that the temperature therein is prevented from rising when the cold air in said auxiliary space is replaced by warm air from without.

Another object of the invention is to provide an improved receptacle for mounting on a wall or partition inside of a refrigerator and which is so constructed that it serves as an air pocket for preventing the temperature of the air therein from rising rapidly when the door of the refrigerator is open.

Another object of the invention is to provide such a receptacle which is transparent so that trapping of the cold air in the pocket defined by the receptacle will not interfere with visibility for determining the contents of the receptacle.

Other objects and advantages of the invention will become apparent from the following specification, the drawings to which it relates, and from the claims hereinafter set forth.

Fig. 1 is a front view, partly broken away, of a refrigerator embodying the invention;

Fig. 2 is a sectional view on line 2—2 of Fig. 1; Fig. 3 is a detail sectional view on line 3—3 in Fig. 2;

Fig. 4 is a detail sectional view on line 4—4 in Fig. 2;

Fig. 5 is a front view, partly broken away, of a refrigerator shelf illustrating a modification of the invention; and

Fig. 6 is a detail sectional view on line 6—6 in Fig. 5.

Referring to Fig. 1, the refrigerator illustrated is provided with refrigerating apparatus including a cooling unit 10 located in the upper left

hand corner of the storage space. At the right side of the unit 10 and below it, is a series of metal drawers 11 for receiving articles of food or the like. The refrigerator is accessible by means of a door 12. As best shown by Fig. 2, the front ends of the drawers 11 when the drawers are in closed position are spaced substantially from the door 12 to provide an auxiliary or front storage space 13.

Referring to Figs. 3 and 4, each of the drawers includes vertically extending side walls 15, a back wall 16, and a front wall or panel 17. For the purpose of slidably mounting the drawers in the cabinet, U-shaped members 18 are welded or otherwise secured to opposed sides of the cabinet, as best shown by Fig. 4, and the front half portion of the upper leg of the member is removed as indicated at 19 so that the upper leg is present only along the rear half of the member. The lower leg of the channel constitutes a support for rollers 20 that are rotatably mounted on the lower portion of double angle members 21 and which project through slots in intermediate portions of the latter. These rollers support the drawers by means of angle irons 22 welded or otherwise secured to the side walls 15 and which rest on the rollers. The members 21 project upward at the side of the angle irons 22 and are provided with auxiliary rollers 23 that substantially contact with the upper side of the angle irons. An arrangement similar to this may be provided on the right side of the cooling unit structure to support the left side of the upper drawer. The rear end portion of the lower legs of the members 21 may have rollers adapted to ride under the upper legs of the channels 18. Since the members 21 only move approximately half the distance that the drawers move, owing to the rolling contact, the rollers will function to prevent downward tilting of the drawers when open. A suitable stop may also be provided to prevent entire removal of the drawers except when desired.

For the purpose of substantially closing the space around the drawers, the front walls 17 extend laterally beyond the side walls 15 as indicated at 25 in Fig. 3 and preferably the side walls of the cabinet will have the metal lining thereof provided with ribs 26 which are closely adjacent to the side edges of the portions 25 when the drawers are in their closed positions. This arrangement is provided for the reason that the overall width of the front wall 17 must be of such dimensions that it can be moved through the door opening and the latter is usually smaller

than the distance between the inner side walls of the cabinet. This rib 28 also is provided along the lower or bottom wall of the cabinet and along the upper wall thereof at the right of the cooling unit so that the upper edge of the wall 17 on the upper drawer will be closely adjacent to the rib while the lower edge of the bottom drawer will similarly be disposed closely adjacent to the rib on the bottom wall. The depth of the front walls 17 of the drawers is such that when the latter are in closed position, only small interstices exist between said front walls, and preferably such edges and also the side edges of the panels will have inturned flange portions 27 to avoid a sharp corner as well as to reinforce the wall structure. This arrangement in effect provides a closed and practically sealed partition between the main storage space into which the drawers project and the auxiliary space 13 when the drawers are closed.

Inasmuch as the cooling unit proper is within the storage space into which the drawers project, air currents will keep this storage space at the low temperature desired, whereas the auxiliary storage space 13 in front of the drawers will be cooled principally by conduction through the front walls 17. The provision of this auxiliary space 13 is advantageous for the storage of articles of food most frequently used and which will be first accessible when the door is opened without rendering it necessary to open any of the drawers. This avoids in many instances opening of the drawers with consequent heating of the main storage space into which the drawers project. Moreover the relatively infrequent opening of the main compartments will tend to conserve the energy used to lower the refrigerator temperature and inasmuch as foods of high moisture content can be stored in the auxiliary compartments which are not included in the air circulation which passes over the cooling unit, the moisture content of such foods will be conserved, thereby avoiding rapid frosting of the cooling unit with the consequent disadvantages of frequent "defrosting" operations and also avoiding in some measure loss of efficiency that results from operation with a heavily frosted cooling unit. For the purpose of allowing air currents to circulate within the main storage space, the bottoms of the drawers are provided with grills or shelves 30 of open construction so that in effect and with the drawers closed, the main storage space will be substantially identical to the storage space ordinarily provided in the conventional refrigerator.

For the purpose of storing articles of food in the auxiliary space 13, receptacles are provided on the front walls of the drawers and in the construction shown by Figs. 1 to 4, these receptacles are formed by extending the side walls 15, as shown by Fig. 3, through openings in the front walls 17 to points in front of the drawers and preferably at the points where these walls project through the front wall 17 a welding connection 31 may be effected. The bottom walls of the receptacles may comprise separate metal panels 32 welded to the forwardly projecting ends of the side walls 15 and to the lower ends of the panels 11 or such panels 32 may constitute integral and outwardly directed portions of the walls 17 which may be subsequently welded to the forwardly projecting portions of the side walls 15. From a manufacturing point of view, forming the panel 32 integral with the wall 17 and then bending them outwardly to form bot-

toms for the receptacles would perhaps be the most economical method of manufacture. The front wall of the receptacle on the drawers comprises a piece of glass or other transparent material 33 which has its edges received in channels 34 formed at the front edges of the forwardly projecting portions of the side walls 15. Thus the receptacles are formed of impermeable walls and the front wall is transparent. While the wall 33 might be composed of metal, the use of transparent material is preferred as it enables the user to see the contents of the receptacle very easily.

As arranged in Fig. 1, one of these receptacles 15 is mounted on each of the drawers and the lower one is of greater depth so as to more readily accommodate articles of greater height such as bottles of milk and the like. Also it will be noted that a smaller receptacle, indicated at 20 37, is provided on the lower drawer and, while this is not essential, it is advantageous under certain circumstances. This smaller receptacle 25 may be formed of metal ends and bottom which may be welded or otherwise secured to the front wall 17. The construction of the receptacles 30 with impermeable walls is of considerable importance and may be briefly explained with respect to Fig. 2 where arrows are shown to indicate the direction of air currents first occurring when the door is opened. Before this door 35 is opened, it may be assumed that the entire auxiliary space is at a fairly low temperature but as soon as the door is opened, this space is exposed to air at a considerably higher temperature and naturally air currents are set up to equalize temperature conditions. The cold air within the space 13 will flow downwardly as indicated by arrows and be supplanted by warm air from the exterior of the cabinet, but this 40 is not true of the cold air within the receptacles as it cannot easily flow upwardly and the impermeable walls prevent its flowing downwardly. Thus this cold air is trapped and a longer period of time will be required before the temperature 45 of the air in these pockets will increase to that exterior to the refrigerator. Usually the user of the refrigerator only opens the door for an instant and this is hardly sufficient to change the temperature of the cold air in the receptacles while it is sufficient to cause a rapid evacuation 50 of the cold air not pocketed. Without receptacles of this character, the space 13 would be quickly warmed when the door is opened as all of the cold air would flow downwardly and outwardly 55 in a short interval of time. It should be appreciated, therefore, that the pocketing of the cold air in the receptacles on the front walls of the drawers will enable more efficient operation of the refrigerator, and furthermore will more efficiently maintain the articles in said receptacles at the required low temperature.

Figs. 5 and 6 disclose a drawer and receptacle 60 that may be used in place of the drawer shown by the first four figures, and in this construction, the receptacles are formed integrally from glass or other transparent material as indicated at 38 and it will be understood that the end walls, front wall and bottom of this receptacle are so constructed of the transparent material. For supporting the receptacles on the front walls 17 of the drawers, integral lips 39 may be provided 65 on the opposite end walls which may have openings 48 for hooking over headed pins 41 on the front wall 17 of the drawer. This arrangement 70 enables removing the receptacle without diffi-

culty while obtaining the advantageous results previously mentioned of avoiding rapid warming of air pocketed within the receptacle and also providing visibility. It may be mentioned here that the drawers will be provided with handles as indicated at 42 so that they may be manipulated easily and pulled out of and pushed into the cabinet.

The invention provides an improvement in refrigerators having drawers for receiving articles of food to be stored and a refrigerator of this character wherein a main storage space and an auxiliary storage are provided. This enables storing food in the drawers and maintaining it at the desired low temperature while still providing an auxiliary space for storing articles of food more frequently used so that when the door of the refrigerator is opened to remove food from this auxiliary space, the main storage space in which the drawers are disposed is not greatly affected by the higher temperature of the air outside of the refrigerator. The secondary receptacles are provided for receiving food that is more frequently used and which are mounted in this auxiliary space and these receptacles are of such character that they pocket cold air and prevent a rapid change in the temperature thereof when the door is opened. This considerably increases the efficiency of the refrigerator and particularly is desirable as under ordinary conditions it maintains the air around the food in the receptacles at a more constantly low temperature.

More than one form of the invention has been illustrated and described in detail, and it will be apparent to those skilled in the art that various modifications may be made without departing from the scope of the following claims.

What is claimed is:

1. A slidable rack for a refrigerator including a front portion having relatively impermeable walls forming the bottom and all sides thereof to retain cold air therein when said front portion is drawn outside of a refrigerator, the back portion of said rack being an openwork structure to permit free circulation of air therethrough.
2. A refrigerator rack as set forth in claim 1 in which at least one of said side walls is transparent to afford visibility for determining location of articles therein.

50

3. A refrigerator including wall structure forming a food space of given depth, a slidable shelf in said food space, said shelf having a front wall and projecting forward from the back wall of the food space a lesser distance than the depth of the food space leaving a front space between the front wall of said shelf and the front wall of the food space, a container in said front space mounted on said shelf, so that the container is moved out of the food space when said shelf is drawn forward, said container having solid walls forming the bottom and all sides, and at least one of said side walls being transparent, to both trap cold air when said container is moved from the food space and afford visibility for determining location of articles therein.
4. A refrigerator including wall structure forming a food space of given depth, a slidable shelf in said food space, said shelf projecting forward from the back wall of the food space a lesser distance than the depth of the food space leaving a front space between the front edge of said shelf and the front wall of the food space, a container in said front space mounted on said shelf so that the container is moved out of the food space when said shelf is drawn forward, said container having solid walls forming the bottom and all sides thereof to trap cold air therein when said container is moved from the food space.
5. In a refrigerator including a cabinet having a chamber for goods to be refrigerated and provided with a doorway, and means for refrigerating said chamber, a plurality of drawers in said chamber, each drawer having a transverse partition behind its front end that divides the drawer into a front compartment and a rear compartment, one of the walls of the drawer forming said rear compartment being perforate to permit the circulation of air from one drawer to another behind the partitions, the bottom and all side walls of the drawer forming said front compartment being solid to trap therein cold air when withdrawn through said doorway, said partitions of the different drawers co-acting to substantially close the portion of the chamber occupied by the rear compartments against the escape of cold air when said shelves are vertically aligned within said chamber.

LOUIS RUTHENBURG.
